LANE JOHNSON, OF INGRAM, PENNSYLVANIA, ASSIGNOR TO UNITED ENGINEERING & FOUNDRY COMPANY, OF PITTSBURGH, PENNSYLVANIA, A CORPORATION OF PENNSYLVANIA

AUTOMATIC CROPPING SHEARS

Application filed April 8, 1926. Serial No. 100,655.

This invention relates to the shearing of metal sheets or plates, and especially to machines known in the art as cropping shears for trimming the ends of sheets or other shapes.

The present invention has for its principal object to provide a cropping shear which is automatically controlled by the movement of a sheet to be trimmed into 10 shearing position thereon.

A further object of the invention is to provide, in combination with a suitable conveyor or the like, an automatic cropping shear so arranged with respect thereto that 15 sheets moving therealong may be received by the machine, trimmed, and then passed on along the conveyor.

A further important object of the present invention is to provide a shear of this 20 kind which may be interposed between two rolling mill units arranged in tandem whereby a sheet or plate emerging from one may be cropped and then automatically moved on to the next.

25 The nature and advantages of the present invention may be readily understood by reference to the accompanying drawings in which:

Figure 1 is a diagrammatic plan view of a 30 shear embodying my invention interposed between a pair of rolling mill units;

Figure 2 is a side elevation of the arrangement shown in Figure 1;

Figure 3 is an enlarged plan view of the 35 shear and its driving means;

Figure 4 represents a longitudinal vertical section through the shear; and

Figure 5 is a diagram illustrating a manner of effecting automatic control of the 40 shear.

In the drawings, 2 designates the first 45 rolling mill, 3 the second rolling mill, 4 the forward part of a conveyor or transfer table between the units and 5 the rear part of such table. The automatic shear, designated generally as 6, is interposed between parts 4 and 5 of the transfer means and in effect, really constitutes a part thereof.

The shear has a frame 7 with a rearwardly projecting extension 8. The exten-

sion 8 has a fixed cross bar 9 thereon which holds the upper shear or cutter 10. The bar is held in place by bolts 11 at each end thereof. The cross bar preferably has its forward upper edge 9a slightly rounded for 55 the purpose hereinafter more fully described.

Pivottally supported on a shaft 12 at the forward end of the frame is table 13 having side flanges 14 on its top, and having 60 integral bracing ribs 15 on its under surface. At the rear end of the table is a transverse rib 16 that supports the lower shear or knife 17. The table 13 therefore constitutes the movable lever or carrier for 65 the lower knife or shear.

Pivottally secured to the under side of the table at 18 is the operating link or connection 19 engaging the eccentric 20 of drive shaft 21. The rotation of the drive shaft 70 21 thus serves to rock the movable sheer. In Figure 4 the shear is shown in its lowermost position, and from this position it may be raised until the top of table 13 and the top of cross-rib 16 are substantially flush 75 with the top of the conveyor or transfer table and the top of bar 9.

The shaft 21 may be driven in any suitable way, but preferably through some means readily adaptable to automatic control. For the purposes of the present invention I have shown an electric motor 22 as the driving means and it is connected to shaft 21 through reducing gearing of a conventional type at 24.

In Figure 5 I have illustrated one system of control for this driving means. It constitutes an automatic switch 25 of conventional type in the motor supply circuit. This switch is controlled by the closing of 85 contacts 26 in a control circuit 27. The closing of either of the contacts 26 will start the motor.

The contacts 26 are carried on the rear extension 8 of the machine frame back of 90 and below the cross-bar 9. In this part of the machine frame is a plate 28 which may be adjusted forwardly by bolts 29 and which may be clamped in place by clamp bolts or nuts 30 engaging in slots 31 in the 100

frame. On this plate are flanges 28^a which support slide rods 32. On the forward ends of rods 32 is a plate contact strip 33. Springs 34 urge the rods and plate 33 forwardly. The movable element of the control contacts 26 is designated 26^a and one of them is carried on each rod 32. The fixed elements of the contacts are supported on the bed but insulated therefrom. These are 10 designated 26^b.

In the operation of the apparatus, a sheet passes from between the first rolling mill unit along the conveyor or transfer means and its forward end rides down the inclined 15 table 13 of the shear, this table then being in its lowermost position. The advancing end of the sheet moves between the open shears and against plate or strip 33, moving it rearwardly to close the contacts 26 of the 20 motor control circuit, thereby causing the shear to operate.

As the shear moves up, cropping the end of the plate, the plate is elevated; and when the shear reaches its upmost position, the 25 plate will advance over the cross-bar 9 onto the second section of the transfer table and be moved to the second rolling mill unit, or to any point of disposal.

In this manner, successive sheets may be 30 automatically trimmed or cropped, and then moved forward to a succeeding mill unit or point of disposal.

The advantages of the present invention arise out of the provision of a shear which 35 may be interposed between two parts of a transfer table or conveyor, or at the end of a transfer table or conveyor section, and which permits of the continuous advance of sheets or plates in succession. Further advantages arise out of the provision of an 40 automatic control governed by the plates or sheets to be cropped for rendering the operation of the shear entirely automatic. The construction of the movable shear arm 45 in the form of a table to receive the sheets and elevate them whereby the shearing stroke also raises the trimmed sheet to permit of its continued forward movement provides a simple and effective means for facilitating the disposal of the trimmed sheets. 50

While I have illustrated a preferred embodiment of my invention, it will be understood that various changes in the construction and operation thereof may be made 55 within the spirit of my invention and under the scope of my broader claims.

I claim:

1. A cropping shear comprising an upper cross member, a cutter carried thereby, 60 means cooperating therewith and movable relative thereto for performing a shearing operation, and mechanism for actuating said means, said means including a work supporting table movably supported, a lower cross member of less width than the length

of the table, said member being associated with and connected to the table for simultaneous movement of said table and said member on the cutting stroke of the shear, and a cutter carried by the lower cross member. 70

2. A cropping shear including a frame, a pair of shearer members, one of which is movable from below the other shear member into overlapping relation therewith, and a vertically movable work supporting for 75 elevating a sheet from shearing position to a position where it may be passed over said other shear member.

3. A cropping shear including a frame, an upper shear member carried by the 80 frame, a pivoted member in the frame having a second shear member on its outer end for cooperation with the first shear member, the top of said pivoted member providing a work receiving and supporting surface, and 85 means for imparting a shearing motion to the pivoted member.

4. A cropping shear including a frame member, a work receiving table pivotally supported in the frame, a shear member on the outer end of the table, a second shear member for cooperation with the first, said 90 table being movable to raise work supported thereon from below the second shear member to a point where it may pass over the said second shear member, and driving means 95 for the table.

5. The combination with a shear having a vertically movable work support and having upper and lower shears, the latter of 100 which is movable vertically relatively to the other, of driving means for effecting movement of the lower shear and of the work support, and a movable contact element located on the side of the shears opposite the movable work support for engagement by sheets for controlling said driving means. 105

6. The combination with a conveyor or the like having two separated sections, of a 110 cropping shear interposed between the sections having cooperating shearing elements formed with cutting portions, the cutting portions of said elements being arranged below the plane of the conveyor sections, and means for elevating a sheared plate to substantially the plane of the conveyor sections. 115

7. The combination with a conveyor or the like having two separated sections, of a 120 cropping shear interposed between the sections, said shear having cooperating shearing elements formed with cutting portions, the cutting portions of said elements being arranged below the plane of at least one of the conveyor sections, and a vertically movable work supporting means for elevating 125 cropped sheets to substantially the plane of that conveyor section whose plane is above the cutting portions.

8. The combination with a shear having upper and lower shearing knives, of a work 130

supporting table connected with the lower shearing knife, driving means for raising and lowering the lower shearing knife and the table, and a sheet controlled means for rendering the driving means effective.

5 9. The combination with a shear having upper and lower shearing knives, of a work supporting table connected with the lower shearing knife, driving means for raising and lowering the lower shearing knife and the table, a sheet controlled means for rendering the driving means effective, a conveyor means for delivering plates or sheets to the work supporting table and a second 10 conveyor means for receiving sheets after 15 they have been sheared and elevated by the table.

10. In a cropping shear, relatively movable cutting elements, a pivotally mounted 20 work support cooperating with said cutting elements, said work support being pivotally mounted to swing about a horizontal axis on the side of said support remote from the cutting elements, and means effective for 25 producing relative movement between said cutting elements and vertical movement of said work support at predetermined times to shear and move a shape supported thereby, whereby upon completion of the shearing 30 operation the shape may be passed over the cutting elements.

11. The combination with a conveyor or the like having two separated sections, of a cropping shear interposed between the sections having an upper and a lower cutter, 35 means for producing relative movement of said cutters to bring said cutters into shearing relation below the plane of the conveyor sections, and a table movable with the lower 40 cutter for elevating a sheared plate to a position for passing over the upper cutter.

12. The combination with a conveyor or the like having two separated sections, of a cropping shear interposed between the sections having a fixed cutter below the plane 45 of the conveyor sections, a movable cutter cooperating with the fixed cutter, and supporting means movable with the movable cutter for elevating a sheared plate to substantially 50 the plane of the conveyor sections.

In testimony whereof I have hereunto set my hand.

LANE JOHNSON.
